CLAIM

The ornamental design for a bin label, as shown and described.

DESCRIPTION

FIG. 1 is an environmental view of the bin label, shown attached to a bin;

FIG. 2 is an enlarged perspective view of the bin label;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top view thereof; and,

FIG. 8 is a bottom view thereof.

The broken line showing of a bin illustrates the environment of the design and forms no part of the claim.
